[57] CLAIM

The ornamental design for a golf towel, as shown and described.

DESCRIPTION

FIG. 1 is a perspective view of the one side of a golf towel, with one layer folded to an open position showing my new design;

FIG. 2 is a plan view of the side of FIG. 1 with said one layer located in a closed position;

FIG. 3 is a right end elevational view of FIG. 2;

FIG. 4 is a bottom end elevational view of FIG. 2;

FIG. 5 is a plan view of a side opposite that of FIG. 2;

FIG. 6 is a left end elevational view of FIG. 5; and,

FIG. 7 is an upper end elevational view of FIG. 5.
